CLAIM

The ornamental design for an electric thermal cooker, as shown and described.

DESCRIPTION

FIG. 1 is a perspective view of the electric thermal cooker, showing the present design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is a section A-A' of FIG. 6 thereof.

The broken lines and area within the broken lines depict portions of the electric thermal cooker that form no part of the claimed design.
